(57) **CLAIM**

The ornamental design for display screen or portion thereof with animated graphical user interface, as shown and described.

DESCRIPTION

FIG. 1 is a front view of a first image in a sequence according to the claimed design;
FIG. 2 a second image in the sequence thereof;
FIG. 3 is a third image in the sequence thereof;
FIG. 4 is a fourth image in the sequence thereof;
FIG. 5 is a fifth image in the sequence thereof;
FIG. 6 is a sixth image in the sequence thereof;
FIG. 7 is a seventh image in the sequence thereof; and,
FIG. 8 is an eighth image in the sequence thereof.

The appearance of the transition is sequential from FIG. 1 to FIG. 8. The process or period in which an image transitions to another image forms no part of the claimed design. The broken line at the periphery of the figure illustrates the display screen, and the remaining broken lines in the drawings, including the closely-spaced broken line showing of text, numbers and graphical elements, illustrate portions of the animated graphical user interface. None of the broken lines form part of the claimed design.
